UNITED STATES PATENT OFFICE.

JAMES E. LEADLEY, OF CAMDEN, NEW JERSEY, ASSIGNOR OF ONE-HALF
TO JOHN HANLON, OF NEW YORK, N. Y.

PROCESS OF AND APPARATUS FOR MANUFACTURING GAS.

SPECIFICATION forming part of Letters Patent No. 289,281, dated November 27, 1883.

Application filed July 2, 1883. (No model.)

To all whom it may concern:

Be it known that I, JAMES E. LEADLEY, of Camden, in the county of Camden and State of New Jersey, have invented certain new and useful Improvements in Process of and Apparatus for Manufacturing Heating and Illuminating Gas; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to the manufacture of illuminating and heating gas, first, by the distillation of bituminous or soft coal in furnaces and at a suitable temperature to preserve the resulting hydrocarbon gas and oily vapors from destructive decomposition; second, by the decomposition of steam by means of the hot coke produced from the soft coal; third, by the vaporization of liquid hydrocarbon; and fourth, by combining the gases from the coal, the hydrogen and carbonic oxide resulting from the decomposed steam, and the gas and vapors from the hydrocarbon liquid, and converting them into a fixed gas in a heated fixing-chamber.

In carrying out my invention two beds or bodies of fuel are used in separate furnaces or generating-chambers. They are alternately heated up or raised to a state of incandescence by an air-blast, the hotter one being used for decomposing steam, while the one at lower temperature is used for distilling bituminous or soft coal, which is dropped upon the body of fuel in small charges, as required, while at the same time the hot gases from the steam are passed up through the distilling coal for mixing with and carrying off the rich carbureted hydrogen gas and vapors being evolved, and conveying them into the combining and fixing chamber where a fixed gas is produced.

If illuminating-gas is being manufactured, hydrocarbon oil is admitted into the coal-distilling-chamber for better enriching the water gases, and the resulting vapors are united with the gases from the decomposed steam and from the coal, and with them converted into a fixed gas.

An important feature in my process and apparatus is that of providing one highly-heated chamber and bed of fuel in which the steam is decomposed, and one chamber and body of fuel at a lower temperature, in which the soft coal is distilled and the oil vaporized. After the body of fuel has been reduced in temperature in the first chamber by the decomposition of steam, and the soft coal has been reduced to coke in the second chamber, then the steam is shut off and the air-blast admitted to the second chamber till the bed of coke is raised to a state of incandescence. The air-blast is also admitted to the first chamber, if found desirable, for raising its temperature for distilling soft coal. Then the manufacture of gas is resumed by decomposing steam in the chamber most highly heated, and distilling soft coal in the chamber at a lower temperature, and enriching and fixing the gases, as before explained.

During the operation of heating up one or both of the bodies of fuel by the admission of air-blasts thereto, the gaseous products rising from the fuel are burned by an air-blast and utilized in heating up the steam-superheaters and the gas fixing-chamber. The bituminous coal is charged into the distilling-furnace by a tight charging apparatus of peculiar construction, claimed in another application, so that no heat is lost and no air admitted during the charging operation.

My apparatus comprises two decomposing and generating furnaces, each having a steam-superheater in its top and a bed of fuel in its base, a coal-charging apparatus at the top, and connecting air, steam, and oil supply pipes, a fixing-chamber containing refractory material connecting with the generating-furnaces near their tops, an interposed water-box containing water-cooled valves in the connecting-pipes, and a hydraulic seal-box and connecting-pipes.

Having stated the general nature of my process and apparatus, I will now more particularly describe them with reference to the accompanying drawings, which form a part of this specification, and in which—

Figure 1 represents a front elevation of my apparatus. Fig. 2 represents a vertical section through the two generators, illustrating

the operation conducted from left to right through the generators. Fig. 3 represents a similar sectional view, illustrating the operation conducted from right to left through the generators. Fig. 4 represents a side elevation of one of the generators and a vertical section of the fixing-chamber and the hydraulic seal-box. Fig. 5 represents a top plan view. Fig. 6 represents a horizontal section on the line x to x' , Fig. 1, through the tops of the generators, the base of the fixing-chamber, and the water-box containing the water-cooled valves. Fig. 7 represents a horizontal section on the line y through the base of the generators.

15 In the following description the same letters of reference designate like parts in all the figures of the drawings.

The two generating and decomposing furnaces A and A' are constructed of fire-brick, and are covered by tight jackets composed of riveted plates of boiler-iron. Each has a fuel-chamber, B B' , provided with grates b b' , and a steam-superheating chamber, C C' , above, separated from the fuel chamber by a perforated arch, c c' . The steam-superheating chambers are partially filled with refractory brick-work laid in the usual form of regenerators and resting on the perforated arches c c' . The upper part of each chamber is charged with iron scraps or turnings d d' , resting upon the brick-work. A vertical retort or charging-chute, a a' , extends centrally through each superheating-chamber, through which the coal and oil are supplied to the distilling-chambers.

35 An oil pipe, k k' , connects with each chute a a' , and steam-supply pipes l l' connect with the top of each superheating-chamber, by which steam is admitted into the iron scraps. The oil is supplied from a tank or reservoir, K , and is forced up by the pressure of water admitted at the bottom of the tank by a pipe, w , from an elevated water-tank, W , having an inlet-pipe connecting with the water-main or other source of supply. The chambers B B' are connected with each other by a pipe, D , opening below the grate of each for the passage of gases from one to the other in either direction, as shown by the arrows in Figs. 2 and 3.

50 Each fuel-chamber is provided at its upper contracted portion with inlet-passages G G' , having tight-fitting caps g g' , for the insertion of bars to remove clinkers and to stir and break up the coke or coal in case it becomes necessary. The passages are given an inclined direction for permitting a better operation of the bars. Doors d d' are provided, opening into the ash-pit of each furnace for the removal of ashes, &c., and doors m m' are provided in the tops of the superheating-chambers for the insertion and removal of the iron scraps or turnings. An air-blast pipe, V , connects by branches V' V'' with the ash-pit and the top of each decomposing-chamber B B' , and the branches are provided with gate-valves v v' , for controlling the admission of the blast for blowing up the fuel and for burning the gas.

eous products above the fuel for heating the superheaters and the fixing-chamber. The coal-charging apparatus XX' is mounted above each generator and is composed of cylinders mounted on a revolving disk, so that each cylinder may be made to register with the chute a or a' , which extends down through the superheaters and the arched partitions c c' to the top of the fuel-chambers. The revolving disks carrying the cylinders also carry the smokestacks x x' , having close-fitting caps at their tops for the discharge of products of combustion when desired. When it is desired to discharge products of combustion through the stacks, they are turned to register with the chutes a a' . The charging apparatus is covered by claims in a previous application. The generating-furnaces are connected at the tops of their superheating-chamber C C' by pipes or flues E E' E'' , (see Figs. 2, 4, and 6,) with the base of the fixing-chamber F , below its perforated supporting-arch f '. The pipes E E' extend into the water-box H , where each is provided with a water-cooled valve, e e' , of peculiar construction, and forming the subject of claims in a separate application. In the box the pipes E E' connect at right angles with the pipe E'' , leading back into the fixing-chamber. 95 The fixing-chamber F is constructed of fire-brick, covered by a jacket composed of riveted plates of boiler-iron, and it is mounted upon the columns h , resting upon the brick or stone foundation T . It is filled with regenerator brick-work above the perforated supporting-arch f ', and is provided with a central education-pipe, f , for gas, extending down into the hydraulic seal-box I , and is also provided at the top with a smoke-stack, Z , having a tight-fitting cap, Z' . An air-blast pipe, V , having a valve, v ', connects with the base of chamber F , for supplying air to support combustion of gases used in heating up the chamber. A pipe, I' , conducts the gas from the hydraulic seal-box I to the purifier or scrubber or holder, as desired.

Having described the construction of my improved apparatus, I will now describe the operation carried out therein for the production of illuminating or heating gas, as follows:

The entire apparatus is first heated up by internal combustion of fuel and gaseous products to the desired temperature for successfully manufacturing gas by the decomposition of steam, distillation of soft or bituminous coal, vaporization of oil, and the combining and fixing of the gases and vapors from the different sources, each chamber being heated 125 to the particular degree best suited for performing its particular function. Fires are first kindled in the chambers B B' of the generators with anthracite coal or coke, the fuel being gradually fed in and the combustion thereof urged by air blasts admitted through pipes V V' till two beds of highly-heated fuel, each 130 two or more feet thick, are formed. During this operation of firing up, the gaseous pro-

ducts, containing a valuable per cent. of carbonic oxide, are burned by the admission of air-blasts through pipes V^2 above the fuel, and the hot products of combustion are utilized for heating the refractory brick-work and the iron-scrap in superheating-chamber C' and the brick-work in fixing-chamber F. Should any combustible gas pass into chamber F, it is completely consumed by a blast of air admitted to the base of the chamber by pipe V^3 , and, if desired, the gaseous products may be conducted, previous to their combustion, through chambers C' directly into the fixing-chamber F, and there burned. The combustible gases may be burned partially in chambers C' and partially in chamber F, as found desirable or necessary for heating the chambers to the proper degree for superheating steam and fixing the gases and vapors. In the first instance the bed of fuel in chamber B, which is first used to decompose steam, is raised to the highest temperature, preferably to an incandescent state, while the bed of fuel in chamber B' is raised to a lower temperature, only sufficiently high to properly distill bituminous coal. The air-blasts are then shut off and the caps at the tops of the smoke-stacks are closed. Steam is then admitted by a number of pipes, l , into the highly-heated iron-scrap or turnings at the top of chamber C, and is therein partially decomposed, hydrogen being set free. Then the hydrogen and undecomposed steam are passed down through the highly-heated bed of fuel in chamber B, where decomposition is completed, and the resulting hot gases are conducted, as illustrated in Fig. 2, in the directions of the arrows, into the bed of fuel in chamber B', where any carbonic acid in the gases is converted into carbonic oxide. About the time that steam is admitted to the top of chamber C, a charge of soft coal is dropped through chute a' upon the cooler bed of fuel in chamber B', and the distillation thereof commenced. A small stream of oil, if required for enriching the gases, is also passed into the chute and vaporized. The hot-water gases, before mentioned, pass up through the distilling bituminous coal and carry off the rich carbureted hydrogen gas and vapors being evolved therefrom, and also unite with the vapors or gas from the oil, and they all pass through chamber C' into the fixing-chamber F, where they are converted into a fixed homogeneous gas of high candle power. The operation just described is continued till the bodies of fuel and the superheating and fixing chambers are reduced too low in temperature for successfully carrying on the operation of making gas. Then the steam and oil are shut off, and the air-blasts are again admitted for heating up the beds of fuel and the superheating and fixing chambers in the manner previously described, the cap Z' at the top of stack Z being at the time opened for conducting off the waste products of combustion. During the period that the air-blasts are admitted to both furnaces A A', both of the valves

e e' are opened for admitting the gaseous products into fixing-chamber F. During the period in which steam is passed into chamber C, and the gases are passed from left to right through chambers B' and C', as illustrated in Fig. 2, valve e is closed and valve e' is opened, and when the gases are passed in the reverse direction the valves are reversed in position—that is, valve e' is closed and valve e is opened.

In the second operation of heating up, the body of fuel in chamber B', composed largely of coke from the soft coal previously distilled in such chamber and the superheating-chamber C', are most highly heated, as they are now to be used for superheating and decomposing steam. At the time of heating up the fuel-chambers hot gaseous products containing carbonic oxide are passed up through the oxidized metal scrap in the top of chamber C and de-oxidizes it, the carbon of the carbonic oxide gas uniting with the oxygen of the oxidized metal, reduces the latter to the metallic state, so that it will be again in condition for decomposing steam. The oxidized metal produced by the passage of steam through it is thus repeatedly revivified or changed to the metallic state by the passage of carbonic oxide or other carbureted gas through it, so that the same body of metal may be used over and over again for decomposing steam. The bodies of fuel and the superheating and fixing chambers being the second time properly heated, the air-blasts are shut off, the caps at the tops of the stacks are closed, valve e' closed and valve e opened. Then steam is superheated and decomposed by passage down through chamber C' and the hot bed of fuel in chamber B', and the resulting gases are thence passed to the left, as illustrated in Fig. 3, up through the distilling coal in chamber B, taking up and carrying off gases and vapors from the coal and oil admitted to this chamber, and carrying them into the fixing-chamber F, where they are converted into a homogeneous fixed gas, as in the first instance. The operation of making gas is thus carried on alternately in opposite directions in the two generators, the steam always being admitted to and decomposed in the generator at the higher temperature, and the soft coal being always charged into and distilled in the generator at the lower temperature.

It is seen that by my process soft or bituminous coal is profitably distilled, and the rich illuminating-gases therefrom saved without the wasteful production of soot or lamp-black, and that beds of coke are thus obtained for the subsequent decomposition of steam. During a run for the production of gas, one or several charges of soft coal may be dropped into the distilling-chamber, depending upon the size of the charges and the progress of the distillation. During the operation of firing up, the waste products of combustion are readily passed out of the stack Z, as its cap is open and the lower end of the gas-eduction pipe f

is sealed in the hydraulic box I; but while gas is being made the cap Z' is tightly closed and the gas compelled to pass down through the liquid in the seal-box, and is thence passed off by pipe I' to the place of storage or use. By passing the steam down through the fuel it spreads more uniformly through it, and is thus brought more intimately in contact with every portion of the carbon, and is therefore better decomposed and the fuel is better utilized.

Having described my invention, what I claim, and desire to secure by Letters Patent, is—

1. The process of generating gas, which consists in superheating steam, then passing it down through a body of incandescent or highly-heated fuel, where it is decomposed, resulting in the production of hydrogen, carbonic oxide, and a small per cent. of carbonic acid, then passing these gases up through a separate body of heated fuel, thereby converting the carbonic acid into carbonic oxide and passing them through a charge of distilling soft coal for carrying off the rich gases therefrom, and finally converting them into a homogeneous fixed gas in a heated chamber.

2. The process of manufacturing gas, which consists in decomposing and superheating steam by passing it through a bed of heated iron-scrap and heated brick-work, and then down through a body of incandescent or highly-heated fuel, then passing the resulting gases through a second body of heated fuel for converting any contained carbonic acid into carbonic oxide, then enriching the gases by passing them through a charge of distilling soft coal and by mixing with them the vapors of liquid hydrocarbon, and finally converting them into a fixed gas by passing them through a heated fixing-chamber.

3. In a gas-generating apparatus, a generator having a fuel-chamber in its base, and a superheating-chamber filled with brick-work and a body of iron-scrap in its upper part, and having a coal-chute passing through its

superheater, in combination with the blast-pipes, the steam and oil inlet-pipes connected as described, and the coal-charging apparatus, as and for the purpose described.

4. The generator constructed with a fuel-chamber, a superheating-chamber as described, and having the connected air-blast, steam and oil inlet-pipes, in combination with the fixing-chamber, the connecting-pipe, water-box, and water-cooled valve, as and for the purpose described.

5. A gas-generating furnace having a fuel-chamber in its base, and a superheating-chamber containing refractory material in its upper part, in combination with steam and oil pipes, and a coal-charging apparatus connecting with the superheater, an a second generator, a pipe connecting the two generators at the base, and a gas-ejection pipe connecting with the superheater, as and for the purpose described.

6. The combination of two generators, each having a fuel-chamber in its base, a superheater and charging-chute in its upper portion, with a pipe connecting them at the base, gas-outlet pipes having valves connecting the superheaters with the fixing-chamber, means for charging coal, and the air and steam connecting-pipes, as and for the purpose described.

7. The two fuel-chambers connected by a pipe at their base, and each having steam-inlet pipes connecting with them at their tops or above the fuel, in combination with the chutes and coal-charging apparatus, the gas-fixing chamber, and the connecting gas-pipes from each fuel-chamber, as and for the purpose described.

In testimony that I claim the foregoing as my own I affix my signature in presence of two witnesses.

JAMES E. LEADLEY.
